Primary Examiner—Martie K. Holtje*Attorney, Agent, or Firm*—Fitzpatrick, Cella, Harper & Scinto[57] **CLAIM**

I claim the ornamental design for a fountain pen, as shown and described.

DESCRIPTION

FIG. 1 is a front elevational view of a first embodiment of a fountain pen showing my new design in an exploded condition;

FIG. 2 is a front elevational view of a second embodiment of my design of FIG. 1 shown in an exploded condition; FIG. 3 is a front elevational view of a third embodiment of my design of FIG. 1 shown in an exploded condition; FIG. 4 is a rear elevation view of FIG. 1; FIG. 5 is a rear elevation view of FIG. 2; FIG. 6 is a rear elevation view of FIG. 3; FIG. 7 is a right side elevation view of FIG. 1; FIG. 8 is a right side elevation view of FIG. 2; FIG. 9 is a right side elevation view of FIG. 3; FIG. 10 is a left side elevation view of FIG. 1; FIG. 11 is a left side elevation view of FIG. 2; FIG. 12 is a left side elevation view of FIG. 3; FIG. 13 is a top plan view of the cap member of FIG. 1; FIG. 14 is a top plan view of the cap member of FIG. 2; FIG. 15 is a top plan view of the cap member of FIG. 3; FIG. 16 is a bottom plan view of FIG. 1, showing the end part; FIG. 17 is a bottom plan view of FIG. 2, showing the end part; FIG. 18 is a bottom plan view of FIG. 3, showing the end part; FIG. 19 is a front plan view of FIG. 1, showing the writing tip; FIG. 20 is a front plan view of FIG. 2, showing the writing tip; FIG. 21 is a front plan view of FIG. 3, showing the writing tip; FIG. 22 is a bottom plan view of the cap member of FIG. 1, with the pen body removed for convenience of illustration; FIG. 23 is a bottom plan view of the cap member of FIG. 2, with the pen body removed for convenience of illustration; FIG. 24 is a bottom plan view of the cap member of FIG. 3, with the pen body removed for convenience of illustration; FIG. 25 is a front elevational view of a fourth embodiment of my design of FIG. 1 shown in an exploded condition; FIG. 26 is a front elevational view of a fifth embodiment of my design of FIG. 1 shown in an exploded condition; FIG. 27 is a front elevational view of a sixth embodiment of my design of FIG. 1 shown in an exploded condition; FIG. 28 is a rear elevation view of FIG. 25; FIG. 29 is a rear elevation view of FIG. 26; FIG. 30 is a rear elevation view of FIG. 27; FIG. 31 is a left side elevation view of FIG. 25; FIG. 32 is a left side elevation view of FIG. 26; FIG. 33 is a left side elevation view of FIG. 27;

FIG. 34 is a right side elevation view of FIG. 25;
FIG. 35 is a right side elevation view of FIG. 26;
FIG. 36 is a right side elevation view of FIG. 27;
FIG. 37 is a top plan view of the cap member of FIG. 25;
FIG. 38 is a top plan view of the cap member of FIG. 26;
FIG. 39 is a top plan view of the cap member of FIG. 27;
FIG. 40 is a bottom plan view of FIG. 25, showing the end part;
FIG. 41 is a bottom plan view of FIG. 26, showing the end part;
FIG. 42 is a bottom plan view of FIG. 27, showing the end part;
FIG. 43 is a front plan view of FIG. 25, showing the writing tip;

FIG. 44 is a front plan view of FIG. 26, showing the writing tip;
FIG. 45 is a front plan view of FIG. 27, showing the writing tip;
FIG. 46 is a bottom plan view of the cap member of FIG. 25, with the pen body removed for convenience of illustration;
FIG. 47 is a bottom plan view of the cap member of FIG. 26, with the pen body removed for convenience of illustration; and,
FIG. 48 is a bottom plan view of the cap member of FIG. 27, with the pen body removed for convenience of illustration.
